UNITED STATES PATENT OFFICE.

HENRY E. BRYANT, OF JACKSONVILLE, FLORIDA.

DESIGN FOR A SEWING-MACHINE TABLE AND STAND.

44,081.

Specification for Design.

Patented May 27, 1913.

Application filed September 23, 1911. Serial No. 651,002. Term of patent 14 years.

To all whom it may concern:

Be it known that I, HENRY E. BRYANT, a citizen of the United States, residing at Jacksonville, in the county of Duval, State of Florida, have invented a certain new, original, and ornamental Design for a Sewing-Machine Table and Stand; and I do hereby declare the following to be a full, clear, and exact description of the invention, such as will enable others skilled in the art to which it appertains to make and use the same.

This invention relates to new and useful improvements in designs for sewing machine table and stand.

The accompanying drawing illustrates a perspective view of my invention.

The sewing machine table and stand includes a supporting frame, there being a plate secured to the top of the supporting frame, there being further a plurality of superimposed drawers depending from the opposite ends of the plate and curved to conform to the shape of the edges of the

plate. An ornamental rail is attached to the rear of the first mentioned plate and has extending upwardly therefrom a pair of curved arms between which is pivoted a mirror which faces the operator of the machine. A vertically extending plate depends from the rear of the plate and is connected to the ornamental rail by a curved arm. A vertical bar extends from one corner of the first mentioned plate and is connected to the adjacent arm of the ornamental rail by a supporting rack as clearly illustrated in the drawing.

I claim—

The ornamental design for a sewing machine table and stand, as shown and described.

In testimony whereof, I affix my signature, in presence of two witnesses.

HENRY E. BRYANT.
